UNITED STATES PATENT OFFICE.

THOMAS ARMSTRONG, OF SARANAC, NEW YORK.

WHIP-SOCKET.

No. 841,479.

Specification of Letters Patent.

Patented Jan. 15, 1907.

Application filed June 14, 1906. Serial No. 321,643.

To all whom it may concern:

Be it known that I, THOMAS ARMSTRONG, a citizen of the United States, and a resident of Saranac, in the county of Clinton and State 5 of New York, have invented a new and Improved Whip-Socket, of which the following is a full, clear, and exact description.

This invention relates to improvements in whip-sockets, the object being to provide a 10 novel and simple means for locking the whip-socket in the socket, thus preventing its removal excepting upon its release by unlocking the retaining mechanism.

I will describe a whip-socket embodying 15 my invention, and then point out the novel features in the appended claims.

Reference is to be had to the accompanying drawings, forming a part of this specification, in which similar characters of reference 20 indicate corresponding parts in all the figures.

Figure 1 is a sectional side elevation of a whip-socket embodying my invention, the section being taken on the line *x x* of Fig. 2. Fig. 2 is a section on the line *y y* of Fig. 1. 25 Fig. 3 is a longitudinal section showing the parts in locking position. Fig. 4 is a side view illustrating the locking means. Fig. 5 shows one of the retaining-springs, and Fig. 6 is a sectional detail showing the device as 30 receiving a whip of the usual construction.

Referring to the drawings, 1 designates the socket to receive the whip-stock 1^a, and movable on the outer side of said socket and in a vertical direction is a collar 2. The socket 35 is provided inward of the collar with a plurality of openings 3 for receiving outwardly-curved portions 4 of spring-retaining devices 5 5^a, the said retaining devices consisting of strips of metal and being alternately riveted 40 to the socket at the upper and lower ends. The collar has an enlarged interior lower portion 6, at the upper end of which is an annular shoulder 7. The collar is connected, by means of arms 8, with a plunger 9, the said 45 connections consisting of pins 10, which pass from the arms through slots 11 in the socket, and arranged between the plunger 9 and a plug 12 in the lower end of the socket is a coiled spring 13.

50 The upper portions of the retaining devices 5 are provided with wings 14, which are curved inward, so that when the parts are in locking position the said wings will engage the whip-stock 1^a and prevent the insertion 55 of a tube or the like to release the wings 14^a

on the lower end of the retaining devices 5^a from their position over a collar 15 on the whip-stock. When the whip-stock is moved downward, a locking-bolt 16 will engage with a tooth in a rack-bar 17, pivoted to the collar 60 2 and held yieldingly in engagement therewith by means of a spring 18. To release the bolt from the rack, a key may be inserted through the keyhole 19 to press its guard against the spring 18. 65

In the operation upon first inserting the whip-stock the parts will be in the position indicated in Fig. 1, when by further downward movement of the whip-stock the collar 2 will be forced downward, so that the annular shoulder 7 by engaging with the curved portions 4 of the retaining devices will force 70 said retaining devices inward, as indicated in Fig. 3.

In Fig. 6 the whip-stock is of the usual construction, or having a button 20 instead of the collar 15. 75

Having thus described my invention, I claim as new and desire to secure by Letters Patent— 80

1. A whip-socket comprising a tubular member slotted at its lower portion and having openings above said slots, spring yielding retaining devices arranged in the socket and having curved portions for passing into the 85 said openings, a collar slidable on the socket and having an interior annular shoulder for engaging with said curved portions, a plunger in the socket, arms extended from the collar, pins passing through said slots for connecting 90 the arms with the plunger, and a spring with which the plunger engages.

2. A whip-socket comprising a tubular member having opposite slots at its lower portion, and also having openings above 95 said slots, retaining devices consisting of spring metal having curved portions for extending into said openings, a collar movable lengthwise on the socket and having an annular shoulder for engaging with said curved portions, the upper ends of said retaining devices having laterally-disposed wing portions, a plunger movable in the socket, arms extended downward from said collar, pins passing through the slots for connecting the 100 arms with the plunger, a spring engaging with the plunger, a rack-bar attached to the collar and extended downward therefrom, and a spring-pressed locking-bolt for engaging 105 with the teeth of the rack-bar. 110

3. A whip-socket comprising a socket member having openings near its upper end, spring members secured in the socket and having outwardly - extended portions for 5 passing into said openings, a collar slidable lengthwise on the socket, the interior lower portion of said collar being enlarged, a spring-pressed plunger movable in the socket, arms extended downward from the collar and having connection with said plunger, a ring on

the whip-stock, and means for locking the plunger and collar in lowermost position.

In testimony whereof I have signed my name to this specification in the presence of two subscribing witnesses.

THOMAS ARMSTRONG.
